FIG. 1 is a front view of a terminal device having a display screen with icon showing our new design; and,

FIG. 2 is an enlarged front view of the area circumscribed by lines 2-2 in FIG. 1.

The sharp-cornered dashed broken-line rectangle in FIG. 1 illustrates the perimeter of the display screen of the terminal device. The dashed broken lines outside this perimeter illustrate portions of the terminal device. The dashed broken-line border in FIG. 2 illustrates the perimeter of an enlarged area of the display screen display in FIG. 1 that is circumscribed by lines 2-2. The dashed broken lines form no part of the claimed design. The dot-dashed broken lines shown in FIGS. 1 and 2 illustrate the bounds of the claim and form no part thereof.
